UNITED STATES PATENT OFFICE.

SYLVESTER B. SHILEY, OF LA MESA, CALIFORNIA.

ACCOMPANIST-HARP.

1,179,233.

Specification of Letters Patent. Patented Apr. 11, 1916.

Application filed May 11, 1914. Serial No. 837,618.

To all whom it may concern:

Be it known that I, SYLVESTER B. SHILEY, a citizen of the United States, and a resident of La Mesa, in the county of San Diego and State of California, have invented certain new and useful Improvements in Accompanist-Harps, of which the following is a specification.

My invention relates to an accompanist 10 harp which is in the form and shape of an ordinary harp or zither, and it is more particularly adapted for accompanying another musical instrument or a vocalist.

The objects of my invention are, first, to 15 provide an accompanist harp upon which any one with some ear for music can readily learn to play accompaniments with other instruments or with a vocalist in all the different keys without having first learned the 20 art of fingering the instrument as is ordinarily done; and second, to provide such an instrument that is simple of construction, durable and easily adjusted.

With these and other objects in view as 25 will appear hereinafter, my invention consists of certain novel features of construction, combination and arrangement of parts as will be hereinafter described in detail and particularly set forth in the appended 30 claims, reference being had to the accompanying drawings and to the characters of reference thereon, which form a part of this specification, in which:

Figure 1 is a perspective view of my instrument complete; Fig. 2 is a side view of 35 my operating lever, and Fig. 3 is a detailed side view on an enlarged scale of one of the adjusting screws.

Similar characters of reference refer to 40 similar parts throughout the several views.

The body 1, strings 2, string support 3, adjusting screws 4, tuning pins 5, plate 6, and operating lever 7, constitute the principal parts of my musical instrument.

The body 1 is shaped as shown best in Fig. 1, hollow, and has a hole in one side, the same as most stringed musical instruments. Upon the upper surface, and close to one edge, is pivotally mounted the operating lever 7. It is so mounted on said pivot that it may be raised and lowered slightly thereon as shown best in Fig. 2.

It is provided on its lower surface with a spring member 7^a which is rigidly secured thereto near its pivotal mounting at one of its ends and its other end swinging loosely. Upon the lower surface of this spring is provided a felt cushion 7^b; this cushion being thicker at the loose end and gradually tapering to the attached end. This spring 60 and cushion is for the purpose of stopping the vibration of the strings before pressure is brought to bear on said strings by said lever. Upon the upper surface of this body 1 is rigidly mounted a hitch bar 3, the inner surface of which is in line with the pivotal mounting of the lever 7. To this string support 3 a plurality of strings are mounted which vary in length and thickness to facilitate the getting of the proper 70 pitch of tone. Near the opposite edge of the body 1, placed in line with said pivotal mounting of the lever 7, is a row of adjusting screws 4. This row of adjusting screws 4 which perform the function of bridges 75 for the strings and string support 3 diverge from each other on lines having a common vertex at the center of the screw 7^c. Each of these adjusting screws 4 is provided near its head with a groove 4^b adapted for holding a string. The string support or hitch bar 3 is provided with a row of hitch pins 3^a each adapted for attaching the end of a string. Parallel to the row of adjusting screws 4, and between it and the outer edge 80 of the sounding board, is a row of tuning pins 5, each adapted for holding the end of a string and for winding a string thereon when said pin is turned. The strings are mounted by attaching one of the ends to 90 one of the hitch pins 3^a in the support 3, and fastening the other end to the tuning pin 5, and having the string, when drawn tight, resting in the groove 4^b. There should be enough of the strings to produce 95 the various tones necessary to form a musical chord and they are placed parallel to one another. The lower tones are produced on the longer strings and increase in pitch from the longest string toward the 100 shortest string. The strings, while open, are tuned to the tones desired. These strings are adjusted in their proper positions by means of the screws 4 so that their

top surfaces are flush with each other to provide a level bearing surface for the lower surface of the lever 7. Radiating from the center of the screw 7^c is a plurality of lines 1^a. These lines are spaced apart from each other one-half tone and are used to indicate the positions where the contacting portion of the lever 7 is to be brought into contact with the strings 2. Twelve of these lines 1^a are shown with the twelfth line positioned midway the length of the strings, marking the octave, the rows of screws or studs 4 marking the first note of the scale. These lines may be indicated with the various letters of the musical scale so as to show the steps and half steps, or sharps and flats if desired, but it is preferable to not so indicate them.

It is obvious that when the instrument is turned to any required key or chord that the same order of interval in tones will be maintained, when the operating lever is brought into contact with the strings at any point; that the tones will become higher in pitch as the lever is moved from left to right or from the end toward the center of the board in contact with the strings, and the tones will be lower in pitch as the lever is moved from right to left in contact with the strings.

The plate 6 which is shown mounted on the edge of the board 1 opposite to the edge on which said lever is pivoted has its upper edge normally projecting above the upper surface of said board and is disposed just enough below the level of the strings to permit the lever to sufficiently depress the strings to prevent them from vibrating except between said lever and the hitch bar. This plate or rail 6 is designed to form a support or stop for the lever 7 to prevent it from being depressed to such an extent as to cause the strings 2 to contact with the board 1 as under no circumstances should these strings ever make such contact. This plate 6 is adjustably mounted on said board preferably by means of transversely extending slots 6' arranged at intervals therein and through which headed screws 6'' extend and which may be loosened and the plate adjusted at the desired height according to the pressure that it is desired the lever shall impart to the strings but at no time should the plate be so high as to hold the lever entirely out of contact with the strings.

Having thus described my invention, what I claim as new and desire to secure by Letters Patent is:

60 1. An accompanist harp comprising a sound board provided with a plurality of strings running parallel with each other and extending longitudinally of the board, a lever pivoted at one end near the edge of said sound board and extending across said

strings, supports for the ends of the strings arranged on lines radiating from the lever pivot, and a plurality of lever positioning indicators arranged in radial alignment with the pivot of said lever.

2. An accompanist harp comprising a sound board provided with a plurality of strings running parallel with each other and extending longitudinally of the board, a lever pivoted at one end near the edge of said sound board and extending across said strings, a plurality of lines radiating from the pivot of said lever and extending transversely across said board, and longitudinally spaced string supports mounted transversely on said board with the lines of said supports passing through said lever pivot.

3. An accompanist harp comprising a sound board, a plurality of strings mounted on said board and running parallel with each other, a lever pivotally mounted at one end at one side edge of the said board and extending transversely across said strings, a plurality of lines radiating from the pivot of said lever and spaced a distance sufficient to change the pitch of the strings a semi-tone of the musical scale when said lever is moved from one line to the line next adjacent, and supports for the ends of the strings arranged on lines radiating from the lever pivot.

4. An accompanist harp comprising a sound board, a lever pivoted at one end to said board and extending transversely thereof, a plurality of parallel strings extending longitudinally of said board, supports for said strings radiating from said lever pivot, a plurality of guide lines on said board beneath said strings spaced apart from each other a semi-tone and radiating from the pivot of said lever, and means carried by said lever for preventing vibration of said strings prior to the pressure thereon by said lever.

5. In an accompanist harp, the combination of a sound board, a plurality of parallel strings stretched across and above the surface of said board, a lever pivoted at one end and extending transversely of said strings, supports for the ends of the strings arranged on lines radiating from the lever pivot, and a damper fixed on one end of the lower face of said lever and having its free end extending toward the free end of the lever, the cushioning face of said damper being thicker at its free end and gradually tapering toward its attached end.

6. An accompanist harp comprising a sound board provided with a plurality of strings running parallel with each other, a lever pivoted at one end near one side edge of said board and adapted to extend across said strings, supports for the ends of the strings arranged on lines radiating from the

lever pivot, a plate mounted on the other side
edge of said board and projecting above the
upper face thereof to form a stop for said
lever, said plate being adjustably mounted
5 on said board to vary its position in rela-
tion to said strings.

In testimony whereof, I have hereunto

subscribed my name in the presence of two
subscribing witnesses.
